(57) **CLAIM**

The ornamental design for a light as shown and described.

DESCRIPTION

FIG. 1 is a perspective view of a light showing our new design;

FIG. 2 is another perspective view thereof;

FIG. 3 is a front view thereof;

FIG. 4 is a rear view thereof;

FIG. 5 is a top view; the bottom view being a mirror image thereof;

FIG. 6 is a right side view, the left side view being a mirror image thereof;

FIG. 7 is a perspective view of another embodiment thereof;

FIG. 8 is another perspective view thereof;

FIG. 9 is a front view thereof;

FIG. 10 is a rear view thereof;

FIG. 11 is a top view; the bottom view being a mirror image thereof;

FIG. 12 is a right side view, the left side view being a mirror image thereof;

FIG. 13 is a perspective view of another embodiment thereof;

FIG. 14 is another perspective view thereof;

FIG. 15 is a front view thereof;

FIG. 16 is a rear view thereof;

FIG. 17 is a top view; the bottom view being a mirror image thereof; and,

FIG. 18 is a right side view, the left side view being a mirror image thereof.

The broken lines illustrate portions of the light and form no part of the claimed design.

1 Claim, 11 Drawing Sheets
